[57] CLAIM

The ornamental design for a bowling glove, as shown and described.

DESCRIPTION

FIG. 1 is a top plan view of a bowling glove showing my new design;

FIG. 2 is a bottom view thereof;

FIG. 3 is a right side elevational view thereof;

FIG. 4 is a front view thereof;

FIG. 5 is a left side elevational view thereof; and,

FIG. 6 is a rear view thereof.

The broken line showing of a hand in FIGS. 1-3 is for illustrative purposes only and forms no part of the claimed design.

FIG. 1

FIG. 2

FIG. 3

FIG. 4

FIG. 5

FIG. 6
